UNITED STATES PATENT OFFICE.

JOSEPH D. RAYON, OF BEAUMONT, TEXAS, ASSIGNOR OF ONE-FOURTH TO J. E. JOSEY, ONE-FOURTH TO R. C. MILLER, AND ONE-FOURTH TO C. C. CHINSKI, ALL OF BEAUMONT, TEXAS.

CHICK-BROODING MACHINE.

Application filed May 7, 1927. Serial No. 189,703.

My invention relates to chick brooders, more particularly to that class of chick brooders having a canopy positioned above a burner or heater to diffuse the heat.

It has been customary in the past to provide a brooder of the class described with a solidly constructed canopy positioned above the heater or burner to diffuse the heat. No provision was made to change the shape of the canopy by an adjustment of the same in the process of brooding the chicks in order to regulate the diffusion of heat. A damper, located generally at the top of the canopy, was the only means to aid in the diffusion of heat, except possibly a target or diaphragm. The damper opening was the only large opening in the canopy with the exception of a door in some makes to give the operator access to the heater or burner. In this type of brooder most of the utilized heat generated by the heater or burner is directed to the floor of the brooder house under and just a little beyond the canopy; an indeed very limited area. In order to successfully house a large brood of chicks it is necessary to diffuse the heat of the heater or burner over a large area, especially during the night-time. Unless the heat is well diffused about the brooder there will be crowding of the chicks and a consequent loss in lives.

The objects of my invention are: first, to provide a chick brooder of this class having a canopy made of sections or wings so arranged that it may be easily opened or closed for the purpose of attaining a more favorable diffusion of heat and better ventilation in the process of brooding chicks or other domestic fowls; second, to provide a novelly constructed and operated apparatus of this class.

With these and other objects in view, as will appear hereinafter, my invention consists of certain novel features of construction, combination, and arrangement of parts and portions as will be hereinafter described in detail and particularly set forth in the appended claims, reference being had to the accompanying drawings and to the characters thereon, which form a part of this application, in which:

Figure 1 is a perspective view of my invention, showing by dash-dot lines the open position of the canopy roof sections or wings and other correspondingly shifted parts. 55

Figure 2 is a plan view of the same, showing by dotted lines certain hidden parts of device used to open or close the canopy sections or wings. 60

Figure 3 is a vertical section of same, taken on line 3—3 of Figure 2, showing by dash-dot lines the open position of canopy sections or wings and other correspondingly shifted parts. 65

In the drawings, similar reference characters will be used to designate corresponding parts throughout the several views. 65

My chick brooder consists of preferably an oil burner 11, a feed line 12 to supply oil to the burner from the reservoir 13, a canopy 70 comprising a supporting frame made of metal legs 14 secured to a metal plate 15 and having a top or roof made of several sheet-metal sections or wings 16 secured to the plate 15 by means of hinges 17, a device to 75 open or close the sheet-metal sections or wings 16 and consisting of a wooden handle 18 secured to the reciprocating metal rod 19 which is held in a vertical position by the plate 15 and the guide 20 which is in turn 80 secured to the plate 15, a circular metal plate 21 secured to the rod 19, metal levers 22 secured to the sections or wings 16, and a combined stop and lock 23 secured to the rod 19. By applying a downward pressure 85 with the hand on the handle 18 the rod 19 and plate 21 are caused to move downward. The downward movement of the plate 21 forces the ends of the levers 22 next to said plate to move downward and at the same 90 time causes the opposite ends of the same said levers together with the sections or wings 16 to rise, the sections or wings 16 swinging on the hinges 17. A combined stop and lock 23 limits the downward movement 95 of the rod 19 and holds the brooder canopy open by engaging with guide 20. By tripping the lock 23 the canopy is closed.

During the day time when the air is likely to be moving swiftly in the brooder house 100 owing to the activity of the chicks and open windows the canopy of my brooder is kept

closed. This prevents currents of air from disturbing the flame of the burner. More or less foul air tends to collect beneath the canopy but owing to the swift movement of the air during the day no bad effects result. When the canopy is in the closed position the heat of the burner is directed to the floor under the canopy. It is too hot for chicks to sleep under the canopy but it does well for them to run under the canopy and get warmed in an instant. This they repeat at pleasure.

During the night time when the brooder house is more or less closed and the chicks are still there is little movement of the air. In this still atmosphere it is necessary that the brooder should aid ventilation and not keep any foul gases near the floor. The heat should also be diffused over a large floor area so as to reach all the birds. These objects are attained by keeping the canopy of my brooder open during the night. It is an imitation of the mother hen when she spreads her wings to hover her brood.

From the description given it is obvious that my brooder has distinct advantages over the old type of canopy brooder. In the old type brooder there is usually a damper control in the top of the canopy. When this damper is open it does not cause an efficient distribution of the heat about the chicks. Most of the heat escapes. Whereas, in my type of canopy the heat is more efficiently diffused about the chicks and it is not allowed to escape immediately above the

burner. The plate 21 serves as a target for the flame of the burner.

It is to be understood that the form of my invention herein shown and described is to be taken as a preferred embodiment of the same, and that various changes in the shape, size and arrangement of parts, may be resorted to, which, do not depart from the spirit of my invention, or the scope of the sub-joined claims.

Having thus described my invention, what I claim is:

1. A chick brooder consisting of a heater and a canopy positioned above the heater to diffuse the heat, said canopy comprising a supporting frame, a roof made of wings hinged to said supporting frame, a manual means for either opening or closing said wings, and a combined stop and lock to limit the movement of the said wings and also to hold them open.

2. A chick brooder consisting of a heater and a canopy positioned above the heater to diffuse the heat, said canopy comprising a supporting frame, a roof made of wings hinged to said supporting frame, said wings capable of being manually opened or closed, by levers secured to them and actuated by means of a plate secured to a vertically positioned reciprocating rod mounted on the said supporting frame of said canopy and having a handle secured to said reciprocating rod for manually operating the same.

In testimony whereof I affix my signature.
JOSEPH D. RAYON.
